corporation of New Jersey

Application December 31, 1942, Serial No. 470,902

9 Claims. (Cl. 33—126.5)

The invention relates to stock line recorders for blast furnaces.

Blast furnace installations are provided with stock line recording mechanism for indicating the height of the stock in the furnace. The usual arrangement is to provide one or more rods which extend downwardly from the top of the furnace onto the top of the stock. Each rod is connected by a hoisting rope to the hoisting drum of operating mechanism. Connections are also made to indicating mechanism which registers the position of the bottom of the rod in the furnace. The operating mechanism is controlled to lift the rod before a charge is dumped into the furnace and not to lower the rod back onto the charge until after the top of the furnace has been closed. There is advantage in allowing the rod to follow the downward movement of the stock as this causes the indicating mechanism to register the height of the stock between charges. It is also of advantage to know the rate at which the furnace is digesting the charge as this shows whether the furnace is functioning properly.

One object of the invention is to provide mechanism for indicating the movement of the top of the stock in the furnace.

Another object of the invention is to provide mechanism for indicating both the movement of the top of the stock and the height of the stock in the furnace.

The invention involves operating the indicating mechanism from the hoisting drum and operating the hoisting drum in a manner which allows the rod to move with the stock at all times between charges.

In carrying out the invention in accordance with the arrangement which will be described, the hoisting rope for the rod is wound on a hoisting drum which in turn is mounted on an operating shaft so as to be able to rotate with respect thereto. This operating shaft is driven by a motor. An arm secured to the shaft engages an abutment on the drum to effect rotation of the drum to lift the rod. When the rod upon being raised reaches its upper limit of travel further rotation of the drum is stopped. The abutment however is yieldable, to enable continued rotative movement of the operating shaft. This movement operates switching mechanism to bring the motor to a stop. In lowering the rod the abutment is held against the arm by the weight of the rod as the operating shaft is rotated in the opposite direction by the motor. Resilient means is provided between the arm and the drum which acts to prevent further rotative movement of

the drum after the rod in lowering reaches the top of the stock and to prevent any slack developing in the hoisting rope while the rod is engaging the stock. Continued rotative movement of the operating shaft after the drum is stopped moves the arm away from the abutment and operates switching mechanism to bring the motor to a stop. As the stock line shifts in the furnace, the drum is rotated by the resilient means to move the abutment farther from the arm in case of a rise of the stock line and is rotated by the weight of the rod to move the abutment toward the arm in case of lowering of the stock line. When a certain point is reached in the movement of the abutment toward the arm, switching mechanism is operated to cause restarting of the motor to cause the arm to follow the drum.

The indicating mechanism is driven from the drum. This mechanism is arranged to indicate any movement of the stock, preferably in fractions of an inch, and also the distance of the stock line from the top of the furnace in feet. With the above described arrangement of operating mechanism, the position of the drum is always in exact accordance with the position of the rod. Therefore the indicating mechanism is in exact synchronism with the rod so that the movement and the height of the stock are correctly indicated at all times.

Features and advantages of the invention will be seen from the above statements as well as from the description which follows and the appended claims.

In the drawings:

Figure 1 is a simplified schematic representation of a blast furnace installation embodying the invention;

Figure 2 is a somewhat schematic representation of the operating mechanism for a stock level indicating rod;

Figure 3 is a side view, with parts in section, of the operating mechanism for the rod;

Figure 4 is a view taken along the line 4—4 of Figure 3 with parts omitted;

Figure 5 is a detail taken along the line 5—5 of Figure 4;

Figure 6 is a detail of switching mechanism taken along the line 6—6 of Figure 3;

Figure 7 is a side view of the switching mechanism shown in Figure 6;

Figure 8 is a schematic representation of the indicating mechanism; and

Figure 9 is an "across the line" simplified wiring diagram of the circuits for controlling the operating motor for the rod.

For a general understanding of the invention, reference may be had to Figure 1. The blast furnace 11 is provided at the top with a hopper 12 for receiving the stock from the skip buckets. Upon the stock being dumped onto the hopper it falls on the small bell 13. The small bell in turn dumps the stock onto the large bell 14. When the specified number of loads have been dumped onto the large bell the large bell is opened dumping the charge into the furnace. The small bell 13 is connected by a hollow rod 16 to one end of a lever 17. At its opposite end lever 17 carries a counterweight 18 of sufficient mass to counterbalance the weight of the bell and the rod plus the weight of the load of material resting on the bell. Similarly large bell 14 is connected to a lever 20 by a rod 21 which extends through hollow rod 16. Lever 20 is likewise provided with a counterweight 22 which counterbalances the weight of the bell and the rod as well as the weight of material resting on the bell. The operating mechanism for the bells is not shown.

The mechanism for recording the stock line of the furnace is illustrated as arranged to provide indication at two sides of the furnace. This is effected by providing two rods and operating mechanism for each rod. Each rod 25 extends downwardly through the top of the furnace and is provided at its lower end with a plate 24 resting on the top of the stock. The upper end of 30 the rod is suspended by a hoisting rope 26 which passes over idler pulleys 27 and 28 and thence downwardly to the hoisting drum 30. The rope is helically wound on the drum and has its other end secured thereto. The hoisting drum is rotatably mounted on operating shaft 31 and is operatively connected to the shaft through the intermediary of an operating arm 32 secured to the shaft. This shaft is driven through reduction gearing 33 by an operating motor 34. An 40 electromechanical brake 35 is provided for stopping and holding the motor. A stop motion device 36 is operated by the shaft at the opposite end thereof to control the motor at the limits of travel of the rod. The indicating mechanism 45 37 is driven through a system of Selsyn motors, one designated 38 being driven by the hoisting drum and the other, not shown in Figure 1, being located at the indicating mechanism and connected by wires in conduit 40 to motor 38.

Referring now to Figures 3 and 4, the gear case 45 for the reduction gearing 33 is mounted on a base 46. The operating shaft 31 for the drum 30 extends from the gear case and has a roller bearing 47 on the end thereof. This bearing is held between a shoulder 48 formed on the shaft and a nut 50 secured to the threaded end 51 of the shaft. The drum 30 is mounted on the bearing 47 so as to be free to rotate with respect to the shaft. Oil retaining and protective caps 52 and 53 are provided for the bearing and are secured to the drum as by bolts 54. A driving shaft 49 for the driving Selsyn motor 38 (Figure 1) is secured to cap 52.

The operating arm 32 for the drum extends from a hub 55 which is mounted on shaft 31 between the drum and the gear casing. The hub is secured to the shaft as by a key 56 so that the arm is rotated with the shaft. A roller 59 is provided on the outer end of the arm. A compression spring 57 is provided through which the operating arm acts to effect the lifting of the rod. This spring is mounted on a cylindrical guide 58 extending from a bracket 60 secured to a boss 61 on the drum as by screws 62; see Figure 5. With-

5 in this guide extends a bolt 63 having an abutment 64 on the end thereof adjacent the operating arm. The spring extends between a spring seat formed on this abutment and the bracket 60 and is maintained therebetween in a state of compression by nuts 65 outside the bracket on the threaded end 66 of the bolt. The amount of compression of the spring is such that no movement of the rod within the guide 58 takes place during the lifting of the rod prior to the rod reaching its upper limit of movement. When the rod reaches its upper limit it engages a stop indicated at 67 in Figure 1 which brings the drum to a stop. Continued movement of the operating shaft 31 compresses spring 57 during which movement switching mechanism is operated as will be described later to bring the motor to a stop.

A torsion spring 70 is arranged on the hub 71 of drum 30 and is provided to prevent slack developing in the hoisting rope for the rod when the rod is in position on top of the stock in the furnace. The far end 72 of the spring as viewed from the gear case is hooked over a lug 73 formed on the drum and retained in position by a retaining plate 74 secured to the lug as by bolts 75. The spring extends helically clockwise around the hub and its other end is hooked over a lug 76 on operating arm 32. The strength of the spring and number of turns are such that it may be placed under sufficient tension, as by rotation during assembly of operating arm 32 clockwise as viewed in Figure 4, to maintain the hoisting rope taut but not to lift the rod off the stock. A stop 77 is secured to the drum to engage the operating arm to limit the possible movement by the torsion spring of the drum with respect to the operating shaft.

During the lowering of the rod from its upper limit into position to rest on the top of the stock, the weight of the rod acts through the drum to maintain the abutment 64 in engagement with roller 59. Thus the rate at which the rod is lowered is determined by the rate at which the drum is permitted to rotate by arm 32 and thus by the rate at which the shaft 31 is permitted to rotate by control of the operating motor. When the rod engages the top of the stock the drum comes to a stop due to the action of torsion spring 70. 50 Continued rotative movement of shaft 31, however, moves roller 59 away from abutment 64. During this movement switching mechanism is operated as will be described later to bring the motor to a stop.

55 The switching mechanism operated by continued rotative movement of operating shaft 31 after the drum is stopped is carried by another arm 80 extending from hub 55. This mechanism is mounted on a segment 81 on the end of arm 80 and comprises two switches, one designated 82 for causing the stopping of the operating motor when the rod is stopped at its upper limit of movement and the other designated 83 for causing the stopping of the operating motor when the rod in lowering engages the top of the stock. These switches are of the same construction so that only one of them will be described.

56 Switch 83 is shown in Figures 6 and 7. In the arrangement illustrated this switch comprises a mounting plate 85. Secured to this plate as by screws is a mounting bracket 86 of insulating material having an outwardly extending arm 87. A pair of contact plates 88 are secured as by binding screws 90 to the underside of arm 87. 70 Each plate has a contact tip 91 secured to the

end thereof. These contact tips are engaged by contact tips 92 carried by the ends of contact springs 93. These contact springs are carried by a bracket 94 of insulating material secured to a fulcrum 95 as by screws 96. The contact springs are bridged by a conductor plate 97 and the conductor plate and springs are secured to bracket 94 as by screws 98. The fulcrum 95 is rotatably mounted on a pivot pin 100 secured to the base 85.

The contact springs are moved into and out of engagement with the stationary contacts about pin 100 as a pivot by a toggle. An operating member 105 is pivotally mounted on a pin 106 secured to base 85. An L-shaped bracket 107 is pivotally mounted in the lower end of the operating member. A pin 108 extends upwardly from fulcrum 95 through an aperture 109 provided in the arm of bracket 107. A compression spring 110 is arranged on pin 108 between the bracket and the fulcrum. The operating member 105 is U-shaped at its upper end, the arms 111 and 112 thereof being adapted to engage a lug 113 formed on the inside of the rim of drum 30 to effect the operation of the toggle. A stop pin 114 is secured to plate 85 to be engaged by stop lugs 115 and 116 formed on the bottom of the operating member to limit the amount of movement of the toggle. The plate 85 is secured to segment 81 by screws 117. These screws extend into elongated slots 118 in plate 85 to enable the position of the switch to be adjusted with respect to the operating lug 113.

With the switch in the position illustrated in Figure 6, upon the drum being brought to a stop by the rod engaging the top of the stock, continued movement of arm 80 by shaft 31 in a clockwise direction causes arm 111 to engage lug 113. Further movement results in the toggle being swung to dead center, compressing spring 110 so that as the toggle moves on past dead center the fulcrum 95 is snapped into its opposite position causing the disengagement of the contact springs from the stationary contacts. Lug 115 engages stop pin 114 to limit the opening movement of the switch. The disengaged position of the contact springs is indicated in dot-dash lines in Figure 6.

During the continued movement of the shaft to effect the opening of switch 83, operating arm 32 is rotated along with arm 80, moving roller 59 away from abutment 64. It is to be noted that considerable clearance exists between operating arm 111 and lug 113 in the closed position of the switch. This is to enable arm 80 to have sufficient reverse movement to cause the toggle to be swung back past its dead center and thus effect the closing of the switch before the operating roller 59 engages abutment 64. Upon reverse movement of arm 80 to effect the closing of the switch, the other arm 112 of the operating member engages lug 113 to swing the toggle back to and past dead center. Spring 110 acts as dead center is passed to snap the fulcrum back to its original position, reclosing the switch. The operation of switch 82 is effected in a similar manner and will not be described in detail.

Lugs 120 are formed on arms 32 and 80 and on a third arm 121 extending from hub 55 for supporting an insulating ring 122. Collector rings 123 are secured to the insulating ring and are connected through binding screws 124 to the binding screws 90 of switches 82 and 83. Only three collector rings are illustrated inasmuch as one may serve as a com-

mon feed to each of the two switches. These collector rings are engaged by brushes 125 mounted on a bracket 126 secured as by screws 127 to the gear case 45. These brushes are connected to terminal screws 128 through which they are connected to the control system.

Switches 82 and 83 are utilized to cause the stopping of the operating motor 34 for the rod. These switches are illustrated in simplified control circuits for the motor in Figure 9. The armature of the operating motor is designated 135 and its field winding 136. 137 and 138 are control resistances for the operating motor. The electromagnetic control switches for the operating motor are designated generally by letters as follows:

A Accelerating switch
RH Rod hoisting switch
RL Rod lowering switch

These letters are applied to the coils of the switches and with reference numerals appended thereto they are also applied to the contacts of these switches. The release coil of the electro-mechanical brake 35 is designated BR. CX and CY are contacts on the furnace controller for controlling the sequence of operation of the rod operating mechanism. UL and DL are limit switches provided by stop motion device 36.

In describing the operation of the control system shown in Figure 9, reference may also be had to Figure 2 in which the mechanism is shown for the condition with the rod at some intermediate position between its upper limit and the stock line of the furnace. Assume that the cycle of operation has reached a point where the time for opening the large bell to dump a charge onto the furnace draws near. Prior to the opening of the large bell, and preferably during the last operation of the small bell, controller contacts CX close and controller contacts CY open. The closing of contacts CX completes a circuit for the coil of rod hoisting switch RH. This switch operates to separate interlock contacts RH2, to engage contacts RH3 and RH4 completing a circuit for armature 135 of the rod operating motor and to engage contacts RH1 to complete the circuit for the brake release coil. As a result the brake is released and the rod operating motor starts in operation in a direction to rotate the drum clockwise as viewed in Figure 2, lifting the rod. Initially resistance 137 is in series with the motor armature and resistance 138 by-passes the motor armature. However, as the motor speeds up the coil of accelerating switch A is energized sufficiently to cause the closing of contacts A2 and the separation of contacts A1. This removes the by-pass resistance from the motor armature and short circuits the series resistance, bringing the motor up to full speed. As the rod reaches its upper limit of travel and preferably just before it engages stop 67, up limit switch UL opens breaking the circuit for the coil of accelerating switch A. Thus, contacts A1 reengage and contacts A2 separate connecting by-pass resistance 138 across the motor armature and series resistance 137 in series therewith, causing the motor to slow down. When the rod engages stop 67 the drum 30 comes to a stop. The motor, however, continues rotating at a slow speed moving arm 32 clockwise against the force of spring 57. During this movement operating member 140 of switch 82 engages lug 141 on the drum to swing the operating toggle to and past dead center to effect the

opening of switch 82. This breaks the circuit for the coil of rod hoisting switch RH. This switch drops out to break the circuit for the armature of the rod operating motor and for the brake release coil, with the result that the brake is applied bringing the motor to a stop.

After the charge has been dumped onto the furnace and the large bell has been reclosed, controller contacts CY close and controller contacts CX open. The closing of contacts CY completes the circuit for the coil of rod lowering switch RL. This switch operates to separate interlock contacts RL2, to engage contacts RL3 and RL4 completing the circuit for the armature of the rod operating motor, and to engage contacts RL1 to complete the circuit for the brake release coil BR. Thus the brake is released and the motor operates in a direction to permit the rod to lower by its own weight. During the initial movement of the motor, operating member 140 engages lug 141 to reclose switch 82. During the lowering of the rod the coil of accelerating switch A is short-circuited by contacts RL3 so that by-pass resistance 138 remains connected across the motor armature and series resistance 137 remains in series with the motor armature to give the desired speed for lowering the rod. When the rod engages the top of the stock the drum comes to a stop. The motor, however, continues to rotate with the result that operating arm 32 moves roller 59 away from abutment 64. As this movement takes place operating member 105 engages lug 113 to swing the toggle to and past dead center to effect the opening of switch 83. This breaks the circuit for the coil of rod lowering switch RL. This switch drops out to break the circuit for the armature of the rod operating motor and for the brake release coil with the result that the brake is applied to bring the motor to a stop.

As the stock line lowers in the furnace the rod follows it down as the drum is free to rotate. The drum rotates counterclockwise during this movement, and as this movement continues a point is reached where lug 113 engages and moves operating member 105 into position to reclose switch 83. This effects reoperation of rod lowering switch RL to effect counterclockwise movement of operating shaft 31 with the result that operating member 105 engages lug 113 and causes the reopening of switch 83. This operation is repeated as the stock line lowers in the furnace to permit the rod to follow the stock at all times. Should the stock line for any reason rise, torsion spring 70 causes clockwise rotative movement of the drum to prevent any slack in the hoisting rope. In effecting this operation abutment 64 is moved farther away from roller 59 and lug 113 is moved farther to the right relative to operating member 105. However, this does not effect the operation of switch 83 by lug 113 since when the stock line lowers again counterclockwise movement of the drum takes place and a point is reached where lug 113 effects the reclosing of the switch.

The stock line is usually kept within a certain range in the furnace. However, should the stock line sink below this range the rod follows the stock down until a certain point is reached where down limit switch DL opens to break the circuit for the coil of rod lowering switch RL to bring the rod operating mechanism to a stop. When the time approaches to dump a charge on the furnace, switch 83 usually will be open. Upon the closing of controller contacts CX to cause the

hoisting of the rod, the initial clockwise rotative movement of operating shaft 31 causes the closing of switch 83 and upon the engagement of roller 59 with abutment 64 the drum is rotated to lift the rod as above described.

Thus it is seen that the rod follows the stock at all times between charges. The indicating mechanism is driven from the drum 30 and inasmuch as the drum rotates in accordance with movement of the rod the indicating mechanism is in exact accordance with the position of the rod in the furnace. The indicating mechanism drive comprises a pair of Selsyn motors, one of which is driven from the drum as shown in Figure 1 and the other being located with the indicating mechanism on an indicating panel.

The indicating mechanism is indicated schematically in Figure 8. The driven Selsyn motor is designated 150. This motor operates through a clutch device 151 to rotate shaft 152. On the end of shaft 152 is a pinion 153 which meshes with a gear 154 to form a gear reduction. This gear drives a tubular shaft 155 on the end of which is arranged a pointer 156. This pointer is utilized to indicate the height of the stock in the furnace on a scale 157. Also arranged on shaft 152 is a gear 160 which meshes with a pinion 161 to provide step up gearing. This pinion is on a shaft 162 which extends through tubular shaft 155. On the outer end of shaft 162 is a pointer 163 which is utilized to show the movement of the stock. Mechanism may also be provided for making a permanent record chart of the stock line throughout the operation of the furnace. This mechanism may be driven from gear 154 by means of a pinion 165 and is indicated at 166 in Figure 1.

The scale 157 is laid out in twenty-four equal divisions. The amount of gear reduction provided by pinion 153 and gear 154 is such that for the diameter of drum 30 movement of the pointer 156 over one division represents one foot of movement of the rod. The division marks are numbered in feet from a zero point which represents the bottom of the large bell in closed position. Thus the position of the pointer 156 on the scale between charging operations represents the height of the stock in the furnace. The gear 160 and pinion 161 are so chosen that for the diameter of drum 30 movement of pointer 163 over one division on the scale represents $\frac{1}{2}$ inch of movement of the stock thereby providing a very sensitive indication of the action of the stock in the furnace. Since the hoisting drum follows the movement of the rod, the pointer 163 shows both the rise and fall of the stock and all fluctuations. Thus by simply watching the dial the attendant not only is advised of the height of the stock but also as to how the furnace is digesting the stock.

It is the usual practice to allow about two feet of movement of the rod above the bottom of the large bell before the rod engages its stop. Allowance is made for this movement on the dial by the two unnumbered division marks between twenty-one and zero. Should any stretch of the hoisting rope take place the pointer 156 engages stop pin 167 on the scale 157 to bring the pointer to a stop in position two divisions beyond the zero point. The clutch 151 slips during continued movement of motor 150 until the rod engages its stop 67. Thus upon the lowering of the rod back into the furnace the pointer 156 will reach the zero point on scale 157 as the bottom of the rod comes opposite the bottom of the large bell so

that the indicating mechanism is maintained in step with the rod.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In a blast furnace installation; a stock level indicating rod; a hoisting drum for said rod; driving mechanism for said drum; means connecting said driving mechanism to said drum for relative rotative movement; and means responsive to relative rotative movement of said driving mechanism and said drum for controlling the operation of said driving mechanism.

2. In a blast furnace installation; a stock level indicating rod; a hoisting drum for said rod; driving mechanism for said drum; means connecting said driving mechanism to said drum for relative rotative movement, said drum being rotated with respect to said driving mechanism by movement of said rod in following said stock while said driving mechanism is stopped; means responsive to such rotative movement upon its reaching a certain amount for causing the operation of said driving mechanism to decrease the amount of relative rotative movement between said driving mechanism and said drum; and means operable upon said relative rotative movement being decreased to a certain amount to cause stopping of said driving mechanism.

3. In a blast furnace installation; a stock level indicating rod; a hoisting drum for said rod; driving mechanism for said drum; means connecting said driving mechanism and said drum for movement in a certain position with respect to each other during lifting of the rod off the stock and lowering it onto the stock but to enable relative rotative movement of either with respect to the other; means responsive to movement of said driving mechanism out of said certain position with respect to said drum after the drum is stopped by the rod reaching its upper limit of travel to cause stopping of said driving mechanism; and means responsive to movement of said driving mechanism away from said certain position with respect to said drum while the rod is engaging the stock to cause the stopping of the driving mechanism, and responsive to the movement of said drum toward said certain position with respect to the driving mechanism by said rod in following the downward movement of said stock to cause movement of said driving mechanism away from said certain position with respect to said drum.

4. In a blast furnace installation; a stock level indicating rod; an operating shaft; a hoisting drum for said rod mounted on said shaft and rotatable with respect thereto; driving mechanism for said shaft; an operating member secured to said shaft; an abutment carried by said drum and held in engagement with said operating member by the weight of said rod upon operation of said driving mechanism to lower the rod; means for stopping rotative movement of said drum when the rod engages the stock, continued operation of said driving mechanism after said drum is stopped moving said operating member away from said abutment; means responsive to said movement of said operating member a certain distance away from said abutment for

causing stopping of said driving mechanism and responsive to movement of said abutment to within a certain distance of said operating member by the lowering of said rod to follow the stock to cause restarting of said driving mechanism; and indicating mechanism driven from said drum.

5. In a blast furnace installation; a rod extending downwardly into the furnace; an operating shaft; a hoisting drum for said rod mounted on said shaft and rotatable with respect thereto; driving mechanism for said shaft; an operating member secured to said shaft; an abutment carried by said drum and engaged by said operating member upon rotation of said shaft in one direction to cause lifting of said rod and being held in engagement with said operating member by the weight of said rod upon rotation of said shaft in the opposite direction to lower the rod; means for preventing slack in said rope when the rod is engaging the stock, continued rotative movement of said operating shaft in said opposite direction when said rod is engaging said stock moving said operating member away from said abutment; means responsive to said movement of said operating member a certain distance away from said abutment for causing stopping of said driving mechanism and responsive to movement of said abutment to within a certain distance of said operating member by rotative movement of said drum by the lowering of said rod to follow the stock to cause restarting of said driving mechanism to rotate said operating member in said opposite direction to follow said drum; and indicating mechanism driven from said drum.

6. In a blast furnace installation; a rod extending downwardly into the furnace; a hoisting rope for said rod; an operating shaft; a hoisting drum for said rope mounted on said shaft and rotatable with respect thereto; driving mechanism for said shaft; an operating member secured to said shaft; an abutment carried by said drum and engaged by said operating member upon rotation of said shaft in one direction to cause lifting of said rod and being held in engagement with said operating member by the weight of said rod upon rotation of said shaft in the opposite direction to lower the rod; means responsive to continued operation of said driving mechanism when said rod upon being lifted reaches a predetermined point for causing stopping of said driving mechanism; means for preventing slack in said rope when the rod is engaging the stock, continued rotative movement of said operating shaft in said opposite direction when said rod is engaging said stock moving said operating member away from said abutment; means responsive to movement of said operating member away from said abutment for causing stopping of said driving mechanism and to rotative movement of said drum by the lowering of said rod to follow the stock to cause restarting of said driving mechanism to rotate said operating member in said opposite direction to follow said drum; and indicating mechanism driven from said drum.

7. In a blast furnace installation; a rod extending downwardly into the furnace for resting on the top of the stock; a stop for limiting the upward movement of said rod; a hoisting rope for said rod; a hoisting drum for said rope; an operating shaft, said drum being mounted on said shaft and being rotatable with respect thereto; a motor for operating said shaft; an operating member secured to said shaft; an abutment carried by said drum and engaged by said operating member to cause lifting of said rod upon rotation

of said shaft in one direction and to permit lowering of said rod by its own weight upon rotation of said shaft in the opposite direction, said abutment being yieldable to permit further rotative movement of said shaft in said one direction when the drum is stopped by the rod engaging said stop; resilient means connected between said drum and said operating member for preventing slack in said rope when the rod is engaging the stock; means responsive to continued rotative movement of said shaft in said one direction to cause yielding of said abutment and to rotative movement of said shaft in said opposite direction while said rod is engaging the stock to move said operating member away from said abutment for causing stopping of said motor and to rotative movement of said drum by the lowering of said rod to follow the stock to cause restarting of said motor to rotate said operating member in said opposite direction to follow said drum; and mechanism driven from said drum for indicating the height of the stock in the furnace and the movement of said stock in the furnace.

8. In a blast furnace installation; a rod extending downwardly into the furnace for resting on the top of the stock; a stop for limiting the upward movement of said rod; a hoisting rope for said rod; an operating shaft; a hoisting drum for said rope mounted on said shaft and rotatable with respect thereto; a motor for operating said shaft; a precompressed spring carried by said drum; an operating member secured to said shaft and acting through said spring to cause lifting of said rod upon rotation of said shaft in one direction and to permit lowering of said rod by its own weight upon rotation of said shaft in the opposite direction, said spring yielding when the drum is stopped by the rod engaging said stop to permit further rotative movement of said shaft in said one direction; a second spring connected between said drum and said operating member for preventing slack in said rope when the rod is engaging the stock, said second spring acting during rotative movement of said shaft in said opposite direction to stop rotative movement of said drum when said rod engages the top of the stock; switching mechanism operable by continued rotative movement of said shaft in said one direction after said rod has engaged said stop and by continued rotative movement of said shaft in said opposite direction after said rod has engaged the stock to cause stopping of said motor; an indicat-

ing dial; a pair of pointers for said dial; and means driven from said drum for causing movement of one of said pointers to indicate the height of the stock in the furnace and for causing movement of the other of said pointers to indicate the movement of said stock in the furnace.

9. In a blast furnace installation in which the stock is dumped into the furnace from a bell; a rod extending downwardly into the furnace from the top thereof for resting on the top of the stock; a stop for limiting the upward movement of said rod; a hoisting rope for said rod; a hoisting drum for said rope; an operating shaft, said drum being mounted on said shaft and being rotatable with respect thereto; a motor for operating said shaft; an abutment carried by said drum; an operating member secured to said shaft for engaging said abutment to cause lifting of said rod upon rotation of said shaft by said motor in one direction and to permit lowering of said rod by its own weight upon rotation of said shaft by said motor in the opposite direction; a spring between said abutment and said drum precompressed an amount to prevent further compression thereof during rotation of said shaft in said one direction to lift the rod but to yield when the drum is stopped by the rod engaging said stop to permit further rotative movement of said shaft; switching mechanism operable by continued rotative movement of said shaft in said one direction after said rod has engaged said stop to cause stopping of said motor; a torsion spring on said shaft connected between said drum and said operating member for preventing slack in said rope when the rod is engaging the stock, said torsion spring acting during rotative movement of said shaft in said opposite direction to stop rotative movement of said drum when said rod engages the top of the stock; switching mechanism operable by rotative movement of said shaft in said opposite direction when said rod is engaging the stock to cause stopping of said motor and by rotative movement of said drum by the lowering of said rod to follow the stock to cause operation of said motor to rotate said operating member to follow said drum; an indicating dial; a pair of pointers for said dial; and means driven from said drum for causing movement of one of said pointers to indicate the height of the stock in the furnace and for causing movement of the other of said pointers to indicate the movement of said stock in the furnace.

ARTHUR EDWARD HANDY.
